UNITED STATES PATENT OFFICE.

ARTHUR WELLINGTON BRICE, OF ROCHESTER, NEW YORK, ASSIGNOR, BY MESNE ASSIGNMENTS, TO UNITED SHOE MACHINERY CORPORATION, OF PATERSON, NEW JERSEY, A CORPORATION OF NEW JERSEY.

RHEOSTAT.

1,406,257.

Specification of Letters Patent. Patented Feb. 14, 1922.

Application filed May 16, 1916. Serial No. 97,913.

To all whom it may concern:

Be it known that I, ARTHUR W. BRICE, a citizen of the United States, residing at Rochester, in the county of Monroe and State of New York, have invented certain Improvements in Rheostats, of which the following description, in connection with the accompanying drawings, is a specification, like reference characters on the drawings indicating like parts in the several figures.

This invention relates to rheostats and is designed to provide an improved rheostat of compact construction affording a wide range of adjustment for variable resistance.

Rheostats, as heretofore proposed, have been subject to the disadvantage of affording only a limited number of contact points for introducing fixed amounts of resistance without any means whereby amounts of resistance intermediate these fixed points can be secured. A further disadvantage found in rheostats, particularly those designed for general use, has been the lack of means arranged, under certain conditions, to reduce the adjusted resistance independently of the means by which the resistance has been initially adjusted. It is frequently desirable, when rheostats are interposed in the circuits of translating devices, to provide a normal maximum resistance when the device is inoperative, and momentarily or temporarily to decrease the resistance when the device is in use. It has also been found that, when rheostats as heretofore proposed are used in translating circuits of relatively high voltage very materially to reduce the voltage, the resistance element has become unduly heated, a condition which is dangerous, in that it is possible to burn out the insulation between adjacent strands or convolutions of resistance.

My invention aims to obviate these defects and provides a novel construction of rheostat capable of general use and having certain novel and advantageous forms of adjustment mechanism, as well as a novel and advantageous form of resistance element.

One feature of the invention consists in a rheostat comprising a novel construction

and arrangement of resistance element and co-operating resistance-varying means which, as herein shown, embodies a coil or spiral of resistance material having an edge exposed for contact with a movable contact member constructed for adjustment to engage the exposed edge of the coil from a point adjacent to one end of the coil transversely of the coil for a distance less than its width, and with a second movable contact member constructed and arranged for adjustment to engage the exposed edge of the coil from a point adjacent to the other end of the coil transversely of the coil for a distance less than the width of the coil. Such a construction permits various arrangements of circuit connections, one of which, as shown, enables the second contact member to be placed in a normally open shunt circuit, which, when closed, will cause the second member to act as auxiliary resistance controlling means temporarily to cut out an additional and determined amount of resistance. Preferably, the aggregate transverse adjustment of the two contact members approximates the transverse width of the coil and may be either equal to said transverse width or less than such width. As the two movable contact members operate from opposite sides of the coil, it will be obvious that any desired proportion of the interposed resistance may be cut out and that when a large number of convolutions are contained in the resistance coil the resistance may be "stepped" up or down in relatively small quantities.

A further feature of the invention consists in the combination with an elongated resistance element having an exposed contact face, of a rotatable resistance-varying member having a contact surface, as shown, a spiral rib arranged, when the member is rotated, progressively to engage the exposed face of the resistance element from a point adjacent to one end of said element toward the other end. This arrangement of parts not only insures adequate contact but enables the interposed resistance accurately to be determined and easily to be controlled.

A further feature of the invention consists in a resistance element comprising an

elongated resistance ribbon arranged in insulated convolutions having one edge exposed for contact and constructed,—as shown, transversely corrugated,—, to form a series of ventilating air passages between the ribbon and its insulation and extending transversely of the ribbon face and longitudinally of the ribbon. The series of corrugations provide a series of ventilating 10 openings or air passages between the successive convolutions which are of very material assistance in radiating heat from the resistance material. With a flat coil of this type supported in a horizontal position, the corrugations will form vertically extending passages through which the emanated heat naturally ascends and through which the surrounding and cooler air readily circulates. This cooling air circulation 15 is facilitated by the employment of an enclosing casing for the resistance element with ventilation openings therein.

A further feature of the invention consists in combination with a coil of resistance material having an exposed contact edge, of complementary electrically interconnected movable contact members constructed for adjustment progressively to engage corresponding points in the exposed edges of the 20 coil from adjacent to one end of the coil transversely of the coil in opposite directions. Such adjusting movement may take place from the inner side of the coil outwardly or vice versa, and the provision of complementary contact members substantially 25 increases the surface of electrical contact.

These and other features and advantages will be more clearly apparent from the detailed description following, read in connection with the accompanying drawings, illustrating a preferable embodiment of the invention, and in which,

Figure 1 is a plan view of a rheostat constructed in accordance with the present invention, the cover of the casing being removed;

Fig. 2 is a transverse vertical section through the rheostat with the cover applied to the casing;

Fig. 3 is a diagrammatic view illustrating the rheostat in connection with a translating circuit; and

Fig. 4 is a fragmentary perspective view of the rheostat casing cover showing the adjustment handles with their indicators and dials.

A suitable casing is provided for the resistance element and its controlling mechanism, such as a base 2 provided with laterally offset feet 4 by means of which it may be secured to a suitable support. The base is preferably provided with an annular groove to receive the bottom edge of an annular side 6. A cover plate 8 preferably having its edges downwardly flanged to overlap the

sides, is detachably secured to the frame by suitable means, such as the sleeved bolts 10 extending from the base through the cover plate and clamped thereto by suitable nuts.

The resistance element is supported horizontally intermediate the top and bottom of the casing between a series of spaced pairs of upper and lower grid bars 12, the lower grid bars being supported from the base by suitable posts 14.

The resistance element is in the form of a spiral coil of ribbon 16 of resistance material having its face corrugated transversely and having a strip 18 of insulating material, such as mica, wound between the convolutions of the coil to insulate the separate convolutions from each other. The flat spiral so formed presents a coil of resistance ribbon with exposed edges forming a flat contact surface. These coils are insulated from the grid bars, between which they are supported, by means of plates 20 of insulation inserted between the grid bars and the edges of the coil at the top and bottom. The corrugations of the resistance ribbon 16 form in conjunction with the adjacent convolutions of the strip of insulation, ventilating passages which, in the preferable use of the rheostat, extend vertically so that the heat generated will ascend through these passages and enable the resistance element quickly to radiate any heat generated. Preferably, also, the sides and cover plate of the rheostat casing are provided with apertures to enable the outside and cooler air to circulate through the vertical air passages formed by the corrugations of the resistance ribbon. In the drawings, the corrugations of the ribbon are shown disproportionately large for clarity of illustration and preferably will be substantially reduced to provide an enlarged and more compact structure offering a greater area for resistance regulating contact.

At one side of the casing, service connectors 22 and 24 are provided and are arranged to receive conductors from opposite sides of a service circuit, the current entering, for example, by connector 24. At the opposite side of the casing a series of translating circuit connectors 26, 28, 30 and 32 are provided. The outer end of the spiral of resistance ribbon 16 may be connected as at 34 to a conductor 36 leading to the connector 28. The service current at one side, as the return side, may be connected directly to translating circuit connector 26 by the conductor 38 extending across the rheostat from the service connector 22. The inner end of the spiral of resistance ribbon may be connected to one side of the circuit and a movable contact device is provided which is arranged for adjustment to cut out of the resistance circuit successive convolutions of the coil of resistance ribbon from adjacent to the 130

inner end of the coil transversely and radially outward for a distance less than the transverse or radial width of the coil.

This contact device preferably comprises 5 two spaced contact members electrically interconnected and arranged to engage diametrically opposite corresponding points adjacent to the inner end of the spiral coil 16 and progressively and simultaneously to 10 move uniformly outward transversely and radially of the coil toward the outer edge thereof, progressively cutting out successive convolutions of the spiral coil of resistance. Accordingly, a shaft 40 extends radially of 15 the coil and terminates at points within the outer ends of the spiral. The ends of this shaft are supported in journal blocks 42 having upstanding threaded studs 44 over which connector clips 50 are seated to bear 20 against the blocks 42. A washer 46 of insulating material is seated over the studs and rests upon the upper face of the connector clips 50. A sleeve 48 of insulating material having a flange at its upper end is seated on 25 the studs above the washer 46 and insulates the studs from the apertured ends of leaf spring arms 51 seating over the studs 44 and around the insulating sleeves 48 and appropriately clamped to the bearing block. 30 In the drawings I show a washer and nut seated over the upper end of the stud and clamping the clip and spring arm in place. The spring arms 51 are secured to rigid bars 52, supported by and laterally offset from 35 the grid bars 12 at opposite sides of the rheostat. The spring arms 51 tend normally to press the journal blocks and shaft downwardly toward the resistance member. It should be stated that preferably there are 40 pairs of upper and lower grid bars supporting the resistance element, arranged in two series of spaced bars, each series extending transversely of the spiral in the same direction, one series extending substantially at 45 right angles to the other series. The shaft 40 extends between one of these series of spaced bars 12 and is pressed downwardly in the direction of the exposed edge of the resistance member 16 by the supporting spring 50 arms 51. Mounted on the shaft 40 and extending from points adjacent to the inner end of the resistance member radially outward toward the outer end, are sleeves 54 provided with helical contact ribs 56 positioned to engage corresponding diametrically opposite points in similar convolutions of the coil simultaneously and progressively as the sleeves are rotated. These sleeves are, of course, fixed on the shaft 40, with their 60 contact ribs positioned to engage the inner end of the spiral 16 upon initial rotation of the shaft. The shaft is rotated to secure determinate adjustment of the contact ribs by means of a crown rack 58, which may be 65 segmental or circular, carried by a sleeve 60

clamped on the shaft 40 and insulated therefrom. The shaft 40 is turned to rotate the sleeves 54 and move the contact points of the helical ribs radially outward through a pinion 62 carried on a spindle 70 70 extending through the cover 8 of the rheostat casing and attached to an operating knob 66. The portions of the complementary helical contact ribs 56 positioned vertically above the radial line of contact with the resistance member are always pressed into contact with the exposed edge of the resistance member by the action of the spring arms 51, the use of two contacting ribs insuring ample surface contact. 80

The inner end 68 of the coil 16 of resistance ribbon is connected to a conductor 70 extending from the service connector 24. The connector plates 48 at the supported ends of the shaft 40 are electrically bridged by conductors 72 having their ends connected to each other and to the conductor 70, as at 74. The conductor 70 extends from this point across the rheostat to the translating circuit connector 32. 85

From the described construction it will be evident that the service current will flow from the service connection 24 through conductor 70 to the inner end 68 of the resistance element 16 (assuming that the contact members have not been rotated to engage the exposed edge of the resistance element) and will flow through the successive convolutions of the helical coil 16 to its outer end 34 and thence to suitable translating devices 100 and back to the opposite side of the service circuit. Assuming, however, that the operating handle 66 has been turned to rotate the shaft 40 and position the helical ribs 56 for contact with the exposed edge of the resistance coil at a point between its inner and outer ends, the service current will enter at connector 24 and flow to the contact point of the helical ribs 56 with the helical coil 16, thence around the coil outwardly to its outer 105 terminal and to the translating device or devices and will return to the opposite side of the service circuit. 110

In order accurately to determine the proportion of resistance cut out by the contact point of the helical ribs 56, a pointer 76 is fixed to the spindle 64 of the crown gear at a point adjacent the handle 66, this pointer cooperating with a circular dial 78 which will have imprinted thereon, or otherwise 115 indicated, a scale of the proportion or amount of resistance cut out by the contact points of the helical ribs 56 at the point of adjustment of the shaft 40 indicated by the pointer 76 and dial 78. The pinion 62 120 may be retained in mesh with the crown rack 58, when a segmental rack is employed, by pins 80 co-operating with the pointer 76 to prevent the operating knob from being turned sufficiently far to move the pinion out 125 130

of engagement with the rack teeth of the segment.

A short counter shaft 82 is mounted between spaced pairs of grid bars 12 in the plane of the shaft 40 and at right angles thereto. This counter shaft 82 extends from a point adjacent to the inner end of the coil of resistance ribbon radially outward to a point beyond the outer edge. Its inner end is supported in a bearing block 84 constructed and supported similarly to the bearing blocks 42 heretofore described and similarly supported by a spring arm 86. Mounted on the outer end of the shaft 82 and extending inwardly thereon for a distance to approximate the outermost contact point of the helical ribs 56, is a sleeve 88 fixed to the shaft and having thereon a helical contact rib 90 which extends the length of the sleeve. Adjacent to the end of the sleeve 88 the shaft 82 is supported in a second bearing block 92 constructed similarly to the bearing blocks 42 heretofore described and similarly supported by a spring arm 94. The shaft 82 is designed to be rotated to bring its helical contact rib 90 against the exposed edge of the helical resistance coil 16 adjacent to its outer end and progressively to move its contact point radially inward as the shaft is rotated. Accordingly, a sleeve 96 is clamped on the shaft 82 and insulated therefrom and carries a segmental crown rack 98 arranged to be engaged by a pinion 100 carried by a spindle 102 (Fig. 1) extending downwardly from the cover 8 of the casing and supported therefrom, its upper end being provided with an operating knob 104 and with a pointer 106 co-operating with an annular dial 108 and with stop pins 110 in a similar manner to the spindle 64, knob 66, pointer 76, dial 78 and pins 80 of the main contact adjusting mechanism. In the disclosed construction it is intended that in the position of limit of movement the shafts 40 and 82 will position their contact ribs out of engagement with the helix so that the entire resistance of the helix may be interposed. This arrangement, however, may be varied with different circuit connections.

The shaft 82 with its associated parts and operating mechanism may be electrically connected in such manner as to constitute an auxiliary resistance cut-out. A conductor 112 may be connected to the journal block 84 in a manner similar to the conductor 72 attached to the blocks 42, to extend from the journal block to the translating circuit connector 30 of the rheostat and may be connected in shunt with a portion of the resistance circuit leading to suitable translating devices.

In order clearly to understand the relation of the resistance adjustments afforded by the described mechanism, reference may be had to the diagrammatic view shown in

Fig. 3 of the drawings, in which similar numerals designate similar structural parts and connections as heretofore described.

Assuming that the knob 66 has been rotated to move the contact points of the helical ribs 56 radially outward from the inner end of the helical coil 16, the circuit described will be as follows: from one side of a suitable service source of electric current, such as the generator 114, to the service connector 24 and by conductor 70 and bridging connection 72 to the shaft 40 and to the contact point of the helical ribs 56 with the resistance coil; around the resistance coil 16 outwardly to the outer terminal 34 of the coil, thence by conductor 36 to outlet terminal 28 of the rheostat casing and by a conductor 116 to one side of suitable translating devices indicated generically at 118. From the opposite side of the translating devices, the current will flow by conductor 120 to connector 26 of the rheostat and thence by return conductor 38 to the service connector 22 of the rheostat and back to the opposite side of the current source 114.

The resistance cut-out comprising the shaft 82 with its sleeve and helical contact rib, is connected by the conductor 112 to the connector 30 and extends from this connector by a conductor 122 to a junction with the conductor 116 of the main circuit, a suitable switch or circuit closer 124 being interposed between the connector 30 and the line or conductor 116. This switch may remain open until such time as it is desired to close the shunt circuit temporarily to cut out that portion of the resistance determined by the adjustment and contact point of the helical rib 90.

Assuming that the shaft 40 has been adjusted, as heretofore described, and that the shaft 82 has been similarly adjusted to advance the contact point of the helical rib 90 inwardly of the outer end of the resistance coil 16, the path traversed by the current with the shunt circuit closed through the circuit closer 124, will be as follows: from the current source 114 through service connector 24 and conductor 70 to shaft 40 and the contact point of the helical ribs 56 with the resistance coil; thence through the coil from this point around and outwardly of the coil to the adjusted contact point of the helical rib 90 of the auxiliary resistance cut-out; thence through sleeve 88 and its shaft and by conductor 112 to connector 30 and by wire 122, including circuit closer 124 to the conductor 116, through the translating devices 118 and by return conductor 120, connector 26 and conductor 38 back to the service connector 22 and to the opposite side of the current source 114. In this last circuit, that portion of the coil of resistance material inwardly of the contact points of the helical ribs 56 and outwardly of the contact

point of the helical rib 90, is cut out of resistance during the time the shunt circuit is closed through 124.

It may be desirable in some cases to include in the translating circuit with the translating devices 118, a motor, such as a motor for furnishing the operating power for a machine employing a marking device electrically heated and forming the translating device. In such an event, the conductor 70 at the intake side of the circuit may have a branch 128 extending to connector 32 of the rheostat and, by a conductor 130 having a switch 132 interposed therein, to one side of a motor 126, the current flowing through the motor and from the opposite side of the motor by a conductor 134 to effect a junction with the return conductor 120 of the main circuit. These parts of the motor circuit in the diagrammatic view in Fig. 3 are indicated in light lines, while the main circuit is indicated in heavier lines. The motor circuit may be entirely omitted without interfering with the operation of the main circuit or with the rheostat. In such an arrangement one of the circuit connectors (32) may be dispensed with.

From the foregoing description it will be evident that my invention provides a rheostat of compact construction offering a wide range of adjustment with accurate control and providing in addition, a particularly advantageous construction of resistance element.

The described and illustrated arrangement of circuit connections for the rheostat, while preferable and particularly advantageous, is purely arbitrary, and the circuit connections may be varied for different conditions.

Having thus described my invention, what I claim as new and desire to secure by Letters Patent of the United States is:—

1. A rheostat comprising a spiral of resistance material having an edge exposed for contact, a movable contact member constructed for adjustment to engage the exposed spiral edge transversely from a point adjacent to one end of the spiral across the spiral, and a second movable contact member constructed for adjustment to engage the exposed spiral edge transversely from a point adjacent to the other end of the spiral.

2. A rheostat comprising a spiral of resistance material having one edge exposed for contact, a movable contact member constructed for adjustment to engage the exposed spiral edge radially from a point adjacent to one end of the spiral across the spiral, and a second movable contact member constructed for adjustment to engage the exposed spiral edge radially from a point adjacent to the other end of the spiral.

3. A rheostat comprising a spiral of resistance material having an edge exposed for contact, a movable contact member construct-

ed for adjustment to engage the exposed spiral edge transversely from a point adjacent the inner end of the spiral toward the outer end of the spiral, and a second movable contact member constructed for adjustment to engage the exposed spiral edge transversely from a point adjacent to the outer end of the spiral for a distance less than the width of the spiral.

4. A rheostat comprising a flat coil of resistance material having one edge exposed for contact, a movable contact member constructed for adjustment to engage the exposed edge of the coil transversely from a point adjacent to one end of the coil toward the other end, and a second movable contact member constructed for adjustment to engage the exposed edge of the coil transversely from a point adjacent to the other end of the coil toward said first named end.

5. A rheostat comprising a flat coil of resistance material having one edge exposed for contact, a movable contact member constructed for adjustment to engage the exposed edge of the coil from a point adjacent to the inner end of the coil transversely outwardly, and a second movable contact member constructed for adjustment to engage the exposed edge of the coil from a point adjacent to the outer end of the coil transversely inwardly of the coil, one of said contact members being arranged for connection to a translating circuit.

6. A rheostat comprising a flat spiral of resistance material having one edge exposed for contact, a rotatable contact member constructed for rotary adjustment progressively to engage the exposed spiral edge from a point adjacent to one end of the spiral transversely of the spiral, and a second rotatable contact member constructed for rotary adjustment progressively to engage the exposed spiral edge from a point adjacent to the opposite end of the spiral transversely of the helix toward said first named end, one of said contact members being arranged for connection to a translating device.

7. A rheostat comprising a flat spiral of resistance material having one edge exposed for contact, a rotatable member having a helical contact rib constructed for rotary adjustment progressively to engage the exposed spiral edge from a point adjacent to one end of the spiral transversely of the spiral, and a second rotatable member having a helical contact rib constructed for rotary adjustment progressively to engage the exposed spiral edge from a point adjacent to the opposite end of the spiral transversely of the spiral toward said first named end, one of said contact members being arranged for connection to a translating device.

8. A rheostat comprising a flat spiral of resistance material having one edge exposed for contact, a movable contact member ar-

- ranged for connection to a resistance circuit and constructed for adjustment to engage the exposed spiral edge from a point adjacent to one end of the spiral transversely of the spiral and a second movable contact member constructed for adjustment to engage the exposed spiral edge from a point adjacent to the other end of the spiral transversely of the spiral and arranged for connection in shunt with the resistance circuit.
9. A rheostat comprising a flat spiral of resistance material having one edge exposed for contact, a rotatable contact member constructed for rotary adjustment progressively to engage the exposed spiral edge from a point adjacent to one end of the spiral transversely of the spiral and arranged for connection to a resistance circuit, and a second rotatable member constructed for rotary adjustment progressively to engage the exposed spiral edge from a point adjacent to the first named spiral end transversely of the spiral to and arranged for connection in shunt with the resistance circuit.
10. A rheostat comprising a flat spiral of resistance material having one edge exposed for contact, a rotatable member having a helical contact rib thereon constructed for rotary adjustment progressively to engage the exposed spiral edge along a line from a point adjacent to one end of the spiral transversely of the spiral and arranged for connection to a resistance circuit, and a second rotatable member having a helical contact rib constructed for rotary adjustment progressively to engage the exposed spiral edge along a line from a point adjacent to the opposite end of the spiral transversely of the spiral and arranged for connection in shunt with the resistance circuit.
11. A rheostat comprising a flat spiral of resistance material having one edge exposed for contact and having its ends arranged for connection to one side of a main circuit, a movable contact member arranged for connection to one side of the main circuit and constructed for adjustment to engage the exposed spiral edge from a point adjacent to one end of the spiral transversely of the spiral, and a second movable member arranged for connection in shunt to the main circuit and constructed for adjustment to engage the exposed spiral edge from a point adjacent to the opposite end of the spiral transversely of the spiral for a distance less than the width of the helix.
12. A rheostat comprising a flat spiral of resistance material having one edge exposed for contact and having its ends arranged for connection to one side of a main circuit, a movable contact member arranged for connection to said side of the main circuit and constructed for adjustment to engage the exposed spiral edge from a point adjacent to one end of the spiral transversely of the spiral.
13. A rheostat comprising a flat spiral of resistance material having one edge exposed for contact and having its ends arranged for connection to one side of a main circuit, a rotatable contact member constructed for rotary adjustment progressively to engage the exposed spiral edge from a point adjacent to one end of the spiral transversely of the spiral and arranged for connection to said side of the main circuit, and a second rotatable contact member constructed for rotary adjustment progressively to engage the exposed spiral edge from a point adjacent to the opposite end of the spiral transversely of the spiral and arranged for connection in shunt to the same side of the main circuit.
14. A rheostat comprising a flat spiral of resistance material interposed between a source of current and a translating device having one edge exposed for contact and having its ends arranged for connection to one side of a main circuit, a rotatable contact member constructed for rotary adjustment progressively to engage the exposed spiral edge from a point adjacent to one end of the spiral transversely of the spiral and arranged for connection to said side of the main circuit, and a second rotatable contact member constructed for rotary adjustment progressively to engage the exposed spiral edge from a point adjacent to the opposite end of the spiral transversely of the spiral, said second contact member being arranged for connection in shunt with the same side of the main circuit to which the first mentioned contact member may be connected.
15. A rheostat comprising a casing, a flat spiral of resistance material mounted within the casing and insulated therefrom and having insulation between successive convolutions thereof, a rotatable shaft carrying a contact member constructed for rotary adjustment progressively to engage the exposed spiral edge along a line transversely of the spiral from a point adjacent to one end of the spiral, a second rotatable shaft carrying a contact member constructed for rotary adjustment progressively to engage the exposed spiral edge along a line transversely of the spiral from a point adjacent to the opposite end of the spiral and arranged for connection to the translating circuit, and means for rotating said shafts determinately to position their contacts relatively to the exposed edge of the spiral resistance.
16. A rheostat comprising a casing, a flat spiral of resistance material mounted with-

- in the casing and insulated therefrom and having insulating material interposed between its successive convolutions, a rotary shaft, a helical contact rib projecting from 5 the shaft and constructed for rotary adjustment progressively to engage the exposed spiral edge along a line transversely of the spiral from a point adjacent to the inner end of the spiral, a second rotatable shaft 10 having a helical rib projecting therefrom constructed for rotary adjustment progressively to engage the exposed spiral edge along a line transversely of the spiral from a point adjacent to the outer end of the 15 spiral, means to support said shafts to maintain their helical ribs in contact with the exposed spiral edge, and means independently to rotate said shafts determinately to adjust the contact points of their helical ribs relatively to the convolutions of the spiral resistance.
17. A rheostat comprising a flat spiral of resistance material having an edge exposed for contact, and complementary electrically 25 interconnected movable contact members constructed and arranged progressively to engage opposite points on corresponding convolutions of the spiral from a convolution adjacent to one end transversely of the 30 spiral toward the other end, said contact members being constructed for simultaneous and uniform movement in opposite directions toward the terminal convolution at said other end.
- 35 18. A rheostat comprising a flat spiral of resistance material having one edge exposed for contact, and complementary electrically interconnected rotatable contact members constructed for rotary adjustment 40 progressively to engage the exposed edge of the spiral at opposite points on corresponding convolutions of the spiral from the convolution at one end of the spiral transversely of the spiral toward the other end.
- 45 with means for effecting simultaneous and uniform movement of said contact members in opposite directions along lines transversely of the spiral and toward the terminal convolution at said other end of the spiral.
- 50 19. A rheostat comprising a flat spiral of resistance material having one edge exposed for contact, and complementary electrically interconnected rotatable shafts having helical contact ribs projecting therefrom 55 and constructed progressively to engage opposite points on the convolution of the spiral adjacent to one end and arranged for simultaneous and uniform movement in opposite directions along lines transversely of the 60 spiral and toward the terminal convolution at the opposite end of the spiral.
20. A rheostat comprising a flat coil of resistance material having one edge exposed for contact and arranged to be interposed in 65 a circuit between a source of current and a translating device, a rotatable member arranged for connection to said circuit and having a helical contact rib projecting therefrom, arranged, when rotated, progressively to engage the exposed edge of the coil from 70 a point adjacent to one end of the coil toward the other end.
21. A rheostat comprising a flat coil of resistance ribbon having one edge exposed for contact and forming a flat contact surface and having its face transversely corrugated to form air passages, with insulation between the faces of successive convolutions of the coil.
22. A rheostat comprising a coil of resistance ribbon having one edge exposed for contact and having its face transversely corrugated to form air passages, with insulation between the faces of successive convolutions of the coil.
23. A rheostat comprising a flat coil of resistance ribbon having one edge exposed for contact and forming a flat contact surface and having its face transversely corrugated to form air passages, with a ribbon of 85 insulation wound between the successive convolutions of the coil.
24. A rheostat comprising a casing having ventilation openings in its sides and top, a resistance element supported within 90 said casing between its top and bottom and insulated therefrom and comprising a flat horizontally positioned coil of resistance ribbon having its face transversely corrugated to provide a series of vertical air passages.
25. A rheostat comprising an elongated resistance ribbon arranged in insulated convolutions having exposed edges and constructed to form ventilating air passages extending transversely of the ribbon face and lengthwise of the ribbon.
26. A rheostat comprising an elongated resistance ribbon arranged in insulated convolutions providing a series of ventilating 100 air passages between the ribbon and its insulation.
27. A rheostat construction comprising a casing having ventilating openings in its side, and an elongated resistance element 115 spaced and insulated from the bottom and sides of the casing and arranged in insulated convolutions providing a series of ventilating air passages substantially perpendicular to the bottom of the casing.
28. A rheostat construction comprising a casing having ventilating openings, and a resistance element supported within and spaced and insulated from the walls of the 120 casing and formed in insulated convolutions providing a series of ventilating air passages extending lengthwise of said element.
29. An elongated resistance element arranged to be interposed between a current source and a translating device and having 130

one face exposed for contact, a contact member mounted for adjustment progressively to contact with said face of the resistance from a point adjacent to one end of the resistance 5 toward and from the other end, and a second contact member mounted for adjustment progressively to contact with said face of the resistance from a point adjacent to the other end of said resistance toward and from the 10 first mentioned end, and manually operable means for effecting determinate adjusting movements of said contact members.

30. An elongated resistance element arranged to be interposed between a current 15 source and a translating device and having one face exposed for contact, a contact member mounted for adjustment progressively to contact with said face of the resistance from a point adjacent to one end of the resistance 20 toward and from the other end, and a second and independent contact member mounted for adjustment progressively to contact with said face of the resistance from a point adjacent to the other end of said resistance 25 toward and from the first mentioned end, and manually operable means for effecting determinate and independent adjusting movements of said contact members.

31. An elongated resistance element arranged to be interposed between a current 30 source and a translating device and formed with insulated convolutions having one face exposed for contact, a contact member mounted for adjustment progressively to contact 35 with said face of the resistance from a point adjacent to one end of the resistance toward and from the other end, and a second contact member mounted for adjustment progressively to contact with said face of the resistance 40 from a point adjacent to the other end of said resistance toward and from the first mentioned end, and manually operable means for effecting determinate adjusting movements of said contact members.

45. 32. An elongated resistance element arranged to be interposed between a current source and a transmitting device and formed in insulated convolutions having one face exposed for contact, a contact member arranged 50 to engage said resistance face and mounted for adjusting movement to cut out of circuit portions of said resistance element from one end of the resistance element toward the other end, a second contact member 55 arranged to engage said resistance face and mounted for adjusting movement to cut out of circuit portions of said resistance from the other end of said resistance element toward the first mentioned end, and manually 60 operable means for effecting independent and determinate adjusting movements of said contact members.

65. 33. A rheostat construction comprising an elongated resistance element disposed in insulated convolutions having exposed contact

faces lying in the same plane, a movable contact member arranged for connection in circuit between a current source and a translating device and constructed for adjustment to engage said contact faces from a point adjacent to one end of said element 70 toward the other end, and a second contact member arranged for connection in shunt with said circuit and constructed for adjustment to engage said contact faces from a point adjacent to said other end of the resistance element toward the first named end. 75

34. A rheostat construction comprising an elongated resistance element disposed in insulated convolutions having exposed contact faces lying in the same plane, a movable contact member arranged for connection in circuit between a current source and a translating device and constructed for adjustment 80 to engage said contact faces from a point adjacent to one end of said element toward the other end, a second contact member arranged for connection in shunt with said circuit and constructed for adjustment to engage said contact faces from a point adjacent to said other end of the resistance element 85 toward the first named end, and manually operable means for effecting adjusting movements of said contact members. 90

35. A rheostat construction comprising a coiled resistance element having insulated convolutions presenting exposed contact faces located in the same plane, a movable contact member arranged for connection in circuit with a current source and a translating device and constructed for adjustment to engage said contact faces from a point adjacent to one end of said element toward the other end, and a second movable contact member arranged for connection in shunt with said circuit and constructed for adjustment to engage said contact faces from a point adjacent to said other end of the resistance element toward the first named end. 100

36. A rheostat construction comprising a coiled resistance element having insulated convolutions presenting exposed contact faces located in the same plane, a movable contact member arranged for connection in circuit with a current source and a translating device and constructed for adjustment to engage said contact faces from a point adjacent to one end of said element toward 110 the other end, a second movable contact member arranged for connection in shunt with said circuit and constructed for adjustment to engage said contact faces from a point adjacent to said other end of the resistance element toward said first named end. 115

37. A rheostat construction comprising a 120

- flat spiral of resistance ribbon having insulated convolutions presenting exposed contact edges located in the same plane, a movable contact member arranged for connection 5 in circuit between a current source and a translating device and constructed for adjustment to engage said contact edges from a point adjacent to one end of the ribbon toward the other end, and a second movable 10 contact member arranged for connection in shunt with said circuit and constructed for adjustment to engage said contact edges from a point adjacent to said other end of the ribbon toward the first named end.
- 15 38. A rheostat comprising a flat coil of resistance material having one edge exposed for contact, and a rotatable resistance-varying contact member arranged to be moved progressively to engage said exposed edge with 20 a wiping contact.
39. A rheostat comprising an elongated resistance element having a plane face exposed for contact, and a rotatable resistance-varying member having a spiral contact surface 25 arranged progressively to engage said exposed contact face.
40. A rheostat comprising a spiral resistance element having a plane face exposed for contact, and a rotatable resistance-vary-
- ing member extending transversely of the 30 coils of said element and having a spiral contact rib arranged to be moved by rotation of said member progressively to engage the exposed plane face of the convolutions of said spiral resistance element with a wiping contact.
41. A rheostat comprising a flat coil of resistance material having a face exposed for contact, and a rotatable resistance-varying member having a spiral contact surface 40 arranged progressively to engage said exposed contact face.
42. A rheostat comprising a ribbon of resistance material having one edge exposed and forming a plane contact surface, and 45 having its face transversely corrugated to form air passages.
43. A rheostat comprising a coiled ribbon of resistance material having one edge exposed and forming a plane contact surface, 50 and having its face transversely corrugated to form air passages with insulation between the faces of successive convolutions of the coil.

In testimony whereof I have signed my 55 name to this specification.

ARTHUR WELLINGTON BRICE.

Certificate of Correction.

It is hereby certified that in Letters Patent No. 1,406,257, granted February 14, 1922, upon the application of Arthur Wellington Brice, of Rochester, New York, for an improvement in "Rheostats," errors appear in the printed specification requiring correction as follows: Page 3, line 109, for the word "helical" read *resistance*; page 5, lines 52 and 62, claims 1 and 2, after the word "spiral" insert the words *across the spiral*; same page, lines 73 and 74, claim 3, strike out the words "for a distance less than the width" and insert instead *toward the inner end*; page 6, line 23, claim 9, strike out the word "to", and lines 55 and 56, claim 11, strike out the words "for a distance less than the width of the helix"; same page, lines 124 and 125, claim 15, strike out the words "and arranged for connection to the translating circuit"; page 8, line 47, claim 32, for the word "transmitting" read *translating*; and that the said Letters Patent should be read with these corrections therein that the same may conform to the record of the case in the Patent Office.

Signed and sealed this 19th day of September, A. D., 1922.

[SEAL.]

WM. A. KINNAN,
Acting Commissioner of Patents.
